UNITED STATES PATENT OFFICE

CARL G. SCHULTZ, OF EL RENO, OKLAHOMA

FEED-WATER HEATER

Application filed December 27, 1926. Serial No. 157,369.

This invention relates to a feed water heater for locomotives. The object of the invention is to parallel the temperatures of the water in the boiler of a locomotive and that of the feed water supplied thereto.

5 In carrying out my invention I mount on the boiler of the locomotive a feed water heater through which the feed water from the injector at a temperature of 160° F. flows 10 through a helical pipe within the drum of the heater to the locomotive boiler through a standard boiler check, the temperature of the water being raised to 600° F. by superheated steam drawn from the boiler from a 15 superheat header and led into the drum at the front end and withdrawn therefrom by a pipe terminating at its opposite end and leading through the front to the steam chest of the locomotive. An arrangement of this 20 kind has many important results. It permits supplying a boiler with water at a temperature the same as the water in the boiler; it economizes fuel, saves contraction and expansion of the flues.

25 My invention, therefore, consists of a feed water heater supplied from the injector, said heater consisting of a coil heated by superheated steam. The several features of novelty will be more fully hereinafter described 30 and will be definitely indicated in the appended claim.

In the drawings;

Figure 1 represents in elevation a locomotive boiler containing my improvements.

35 Figure 2 is a sectional view of a feed water heater embodying my invention.

Figure 3 is a sectional enlarged view of Figure 2 showing it mounted in position on a locomotive boiler.

40 Figure 4 is an enlarged end view of one end of the heater or drum.

Referring now specifically to the drawings, 45 1 represents a heater or drum containing my improvements. It is mounted on the boiler 2 of the locomotive by straps 3 secured by

cap screws 4. The feed water on its way from the injector (not shown) in which it is pre-heated to a temperature of about 160° F., is fed into the drum by a pipe 5 in a helical coil of taper form gradually increasing in 50 diameter towards its forward end, as indicated at 6. It may be formed in tubular section of seamless tubing of copper or steel and is securely mounted by longitudinal elastic stays 7, 7a bolted at the ends of the drum. The drum at its ends is provided with heads 8, 8a screwed to annular rings 9, 9a securely riveted into the ends of the drum. Short bolts 10, 10a make and secure a water-tight 55 joint with the drum walls, which may be effected in any suitable way approved by boiler makers. The ends of the coil are threaded and engaged at the respective ends by nuts 11, 11a, to effect a water and pressure tight joint. The end of the feed water 60 coil 6 is connected at the front by a pipe 12 with a standard boiler check to lead the heated feed water into the boiler. A pipe 13 leads through the front end of the drum to a short distance from its inner wall and carries superheated steam from the superheated 65 side of a header 14 mounted in the smoke arch, to which steam is led by a pipe 15, indicated in dotted lines, from the boiler tur- 70 ret 16 through a stop cock 17.

I have herein described the best mode of carrying out my invention and do not limit it to the specific arrangement illustrated but may adopt any equivalent expedients within the scope of my appended claim.

Having thus described my invention, what I claim as new and desire to secure by Letters Patent is:

A feed water heater comprising a drum, 85 heads arranged at the ends of the drum, a feed pipe projecting terminally thereof through the heads at the ends of the drum, said feed pipe having that portion enclosed within the drum shaped to provide a coil of helical taper form, staves of elastic charac- 90

teristics arranged longitudinally within the drum for spacing the coiled portions of the feed pipe from the drum proper, and pipe lines having communication with the interior of the drum through one of said heads being designed to inject and remove superheated steam for the purpose of preheating the water passing through the coiled portions of the feed pipe precedent to final discharge.

10 In testimony whereof I affix my signature.
CARL G. SCHULTZ.
